UNITED STATES PATENT OFFICE.

DAVID McNAB RAMSAY, OF MOUNT FLORIDA, GLASGOW, SCOTLAND.

STEAM-CONDENSER.

1,209,331.

Specification of Letters Patent. Patented Dec. 19, 1916.

Application filed April 6, 1916. Serial No. 89,428.

To all whom it may concern:

Be it known that I, DAVID McNAB RAMSAY, a subject of the King of Great Britain and Ireland, and a resident of Mount Florida, Glasgow, Scotland, have invented certain new and useful Improvements in Steam-Condensers, of which the following is the specification.

The invention has for its object to provide a condenser of surface type of high steam capacity, of high efficiency as regards its consumption of cooling fluid in relation to the cooling surface exposed, and capable of maintaining a high vacuum such as is required for its use for example with steam turbines.

A condenser made according to the invention comprises essentially a series of heat exchanging elements which are alternately and successively immersed in a liquid, which is preferably a cooling medium, and withdrawn, and while moist with that liquid exposed to a current of air.

The heat exchanging units, which are broadly of a type heretofore used in certain forms of cooler, concentrator, and non-vacuum maintaining condenser, may be of any convenient form, for example they may be tubular with tubes of any section or contour desired, or they may be of honeycomb form, or having narrow chambers. Means are provided for leading steam to them, for segregating and extracting the condensate, that is, for so collecting and delivering the condensate that the withdrawal of the air is not impeded, for maintaining a vacuum, and for alternately submerging the units in the liquid and subjecting them to a current of air, the whole being so contrived that the possibility of flooding or choking is prevented and therefore a high internal vacuum is readily maintainable, because air within the condensers has at all times access to the means for maintaining the vacuum.

In order that the invention and the manner of performing the same may be properly understood there are hereunto appended four sheets of explanatory drawings showing an illustrative example of the improved condenser, Figure 1, Sheet 1 being a longitudinal sectional elevation thereof, Fig. 2, Sheet 2 a sectional left-hand end elevation, Fig. 3, Sheet 3 a right-hand end

elevation, while Figs. 4 and 5, Sheet 4 are respectively a sectional end and a sectional side elevation of a detail.

According to this example there is provided a drum like structure consisting of two series A, B of annular segmental headers connected by annular segmental groups C of tubes (for the sake of clearness, only those groups at top and bottom are shown in Fig. 1). The steam to be condensed is admitted by a trunnion pipe D supported in a tubular sleeve E carrying the headers A and supported in a pedestal bearing F. A packing gland G is provided between trunnion pipe and sleeve, and there is fixed to the sleeve a wormwheel H by which the whole is rotated. The steam is directed to the headers A by a cone J and a series of radial blades K which divide it into separate streams for each header. A central shaft L connects the headers A, B, the latter being supported by a spider M thereon, while a disk N serves to support the tube elements at the center of their length.

The segmental headers B are connected with a central discharge manifold P by pipes R which make connection each at one end of a header—that is to say adjacent to the radial partition closing its end. The manifold P is shown enlarged and separate in Figs. 4 and 5, and it will be seen that each pipe R is bent round to deliver in axial line, and that all, pressed to triangular section, are nested together. The pipes deliver directly to the manifold which is supported in a pedestal bearing W and is connected with a discharge pipe X provided with a packing gland Y. The discharge pipe X is connected with any convenient form of pump or pumps adapted to handle the effluent from the condenser and maintain an adequate vacuum therein.

By the manner in which the pipes R are connected to the headers B and the trunnion piece or manifold P, condensate is collected and discharged from the several headers B in such wise that the several condensing elements cannot become flooded or choked with water, the water in each header section being automatically discharged as it passes the highest point during its rotation.

A fan A¹ driven by an electric motor B¹ delivers air to a circular trunk C¹ mounted

on the headers B. The air passes between the pipes R and the arms of the spider M to the space within the tube elements, and from thence passes radially outward through 5 the groups of tubes, cooling them both by evaporation of the film of cooling liquid on their surfaces and by conduction.

A cooling liquid tank D¹ is arranged beneath the rotatory drum structure in such 10 wise that the tube elements and headers dip into cooling liquid in it maintained at the requisite level by a float valve E¹.

In action, the groups of tubes forming the heat exchanging elements are successively 15 immersed in the liquid by the slow rotation of the drum like structure. While immersed, some of the heat of the contained steam may be given up by surface contact 20 of the tubes with the liquid. The elements then emerge coated with a thin film of the liquid which is evaporated by the heat of the tubes and carried away by the current of air to which it is subjected, thus cooling 25 the steam evaporatively.

The essence of the invention lies in providing in combination means in a surface 30 condenser for subjecting the heat exchanging elements alternately to an evaporating liquid and when moist to a current of air, (such being broadly known) and means for segregating the condensate and discharging it in such a manner that a high vacuum is 35 maintainable, and it is clear that the manner of carrying it into effect may be very widely varied from the example just given

which is purely illustrative and in no wise limitative.

What I claim is:—

1. In a condenser having surface heat-exchanging elements, in combination, known 40 means for subjecting the elements (of broadly known form) alternately to an evaporative liquid and when moist therewith to a current of air, known means for supplying steam to be condensed to the elements, means 45 for so segregating and extracting the condensate from the elements that the withdrawal of air is not impeded, means for maintaining a vacuum therein and means for preventing flooding of the elements by 50 the condensate, as set forth.

2. In a condenser a drum like structure, segmental annular headers formed thereby, tube elements connecting said headers, means for supporting and rotating the drum, 55 means for applying cooling medium to the exterior of the tubes and headers, means for admitting steam to the interior thereof, means for abstracting condensate and air and means for so segregating the condensate and air that the air has at all times unobstructed access to the extracting means as 60 set forth.

In testimony whereof I have signed my name to this specification, in the presence of 65 two subscribing witnesses.

DAVID McNAB RAMSAY.
